21 Claims. (Cl. 209—232)

1

This invention relates to magnetic separators of the submerged belt type for separating finely divided magnetic particles from other material. It is particularly adapted among other possible uses, for the separation of magnetic ore particles, such as magnetite, from the gangue.

Heretofore the most successful magnetic separators for such purposes have comprised a carrier belt running over a pair of pulleys and extending in a generally horizontal or somewhat inclined position, with the lower belt stretch sagging along a catenary curve and partially submerged in a settling basin, and with a series of magnet pole pieces extending with a corresponding curvature, along the upper surface of such belt stretch. The material to be treated is fed against the lower surface at one end of the lower belt stretch, whereby the magnetic particles are caused by the series of magnets to adhere to the belt and be carried along to a discharge point, while the non-magnetic particles are being washed from the belt and settle into tailings or middlings hoppers. In such machines it is important to have the belt stretches suspended in loose sagging position, or substantially in accordance with a catenary curve, and with the series of magnet pole pieces following a corresponding curvature. This is because if the belt were pulled tight to conform to a series of pole pieces arranged along a straight line, the conditions are such that among other difficulties, the belt will be quickly pulled apart. While this type of machine, if properly operated, is highly efficient in the sense that the concentrates delivered therefrom will be substantially free of gangue, yet the tailings may embody a measurable amount of unrecovered magnetite, and there is a substantial percentage of the ore which is discharged as middlings and has to be reground and retreated.

According to the present invention, the necessity of using a belt stretch and series of pole pieces with a catenary curvature, is avoided and the percentage of the magnetic particles recovered may be increased. This is accomplished by so positioning the belt that its active stretches will hang substantially vertically, and thus along straight lines without any substantial tensioning. Consequently the series of magnet pole pieces may also extend along a straight line. With the preferred forms of the invention, the belt may be suspended from a single drive pulley located above the liquid level, whereby an elongated loop of the belt extends downwardly along one side of a series of magnets and thence upwardly along the other side of the same magnets. If desired,

2

the lower portion of the belt may run over an additional pulley.

With such vertical positioning of the active belt stretches, the ore may be fed against the belt at areas spaced considerably from the lower part of the belt, and whereby any particles which are not immediately attracted to the belt will have opportunity to fall for a considerable distance along the face of the belt and in the magnetic field, with the consequence that substantially all of the magnetic particles will be captured on the belt before they have opportunity to pass out of the magnetic field, and any magnetic particles which become dislodged from the upper areas of the belt stretches, will have opportunity to be gathered on to the belt again even after falling a considerable distance, and hence will not be lost in the tailings. In the former types of machines where the belt stretches run generally horizontally or in a somewhat inclined position, once any of the magnetic particles have settled or fallen from the belt to points below regions of a relatively strong magnetic field, they cannot be recovered and elevated again against the force of gravity. However, with the vertical belt stretches of the present invention, the magnetic force attracts the particles to the belt either in a horizontal direction or sidewise and downwardly, and hence not in opposition to the force of gravity. And also with the present invention such particles as may be dislodged from the belt during the washing steps have a much greater opportunity to be recaptured since they must fall through a vertically elongated field instead of merely through a generally horizontal shallow field.

The vertical arrangement of the belt stretches also makes it possible to construct a compactly arranged gang separator comprising several of the separating units arranged side-by-side in one housing or tank, and with the active belt stretches of one unit facing corresponding belt stretches of adjacent units. Thus all the space between such facing stretches may be subjected to an intense magnetic field from two units, with a number of consequent advantages hereinafter referred to. Also the vertical arrangement of the belt stretches makes it possible to so arrange the magnets that an active pole piece may be provided at both ends of each magnet, viz., with one pole adjacent the downwardly running belt stretch and the other pole adjacent the upwardly running belt stretch. This makes it possible to greatly reduce, or diminish by half, the number of magnets required and at the same time utilizes

about twice as large a proportion of the belt area, as compared with the prior practice above referred to.

Various further and more specific objects, features and advantages will more clearly appear from the detailed description given below taken in connection with the accompanying drawings which form a part of this specification and illustrate merely by way of example, preferred forms of the invention. The invention consists in such novel features, arrangements and combinations of parts as may be shown and described in connection with the apparatus herein disclosed.

In the drawings:

Fig. 1 is a side elevational view partially in section, showing a gang separator, including several units constructed in accordance with a preferred example of the invention;

Fig. 2 is a horizontal enlarged sectional view of one of the units taken substantially along line 2-2 of Fig. 1;

Fig. 3 is a vertical enlarged sectional view of a portion of one of the units, taken along line 3-3 of Fig. 1; and

Figs. 4 and 5 are vertical sectional views of alternative forms of the invention.

In Fig. 1 a tank or housing is shown at 10 within which a series of separating units as at 11-14 may be mounted. Each of these units may comprise a belt as at 15 formed of suitable non-magnetic material in accordance with known practice. Each of these belts may be suspended and driven by pulleys as at 16. Preferably the peripheral surfaces of the pulleys are made with a notched formation as at 17 to insure against slippage. The pulleys may be mounted on and driven by shafts as at 18 connected to a suitable source of power (not shown). The shafts may be mounted in vertically adjustable bearing blocks as at 19 to provide for adjustment of the suspended loop portion of the belt to the desired height.

The suspended loop portion of the belt may extend down around, and up again over the surface of a U-shaped member 20 formed of thin sheet material such as stainless steel or other non-magnetic material, and serving to provide a magnet compartment. Such compartment has parallel sides and a semi-cylindrical bottom merging tangentially with the sides, which are also preferably in planes tangent to the drive pulley as shown. As shown in Fig. 2, the vertical edges of the member 20 may be sealed along the side walls of the tank 10. The tank 10 may be kept filled with water up to a liquid level such as indicated at L, and the member 20 thus serves to provide a dry housing for the magnets.

A series of superposed electromagnets is shown at A, B, C, D, E. These may be supported at each end, and slideable into or out of position, on rigid bars as at 21, secured to the inside surface of U-shaped member 20. The bars 21 may as shown in Fig. 2, extend from one side wall of the tank 10 to the other, and thereby serve to strengthen the tank as well as the member 20. Further strengthening and supporting means for the tank may be provided as necessary, but for clearness is omitted from the drawings. The side walls of the tank 10 may be cut away over an area shaped to correspond to the shape of the magnet compartment, whereby each magnet may be readily inspected from outside the tank and slid into place or removed on the bars 21 when necessary for further inspection, repair or replacement. The openings in the two side

walls of the tank may if desired be covered by removable cover plates as at 22, 22', for covering each magnet. Suitable detachable electrical connections for the magnets may be provided, but 5 same are omitted on the drawings, for clearness.

If the separating units are of small capacity such that relatively narrow belts may be used, each of the magnets may be formed with pole pieces extending from near one edge of the belt 10 to a position near the other edge. Usually, however, the belts will be of such widths that a pair of magnets as shown at B, B' in Fig. 2 may more conveniently be provided at each elevation. In that case access may be had to one of the magnets of each pair as at B, from one side of the tank 10, while access to the other magnet as at B', may be had from the other side. That is, one-half the magnets may be slidably inserted and removed from each side of the tank upon removing cover plates 22 or 22'.

As shown in Fig. 1, the upper magnets as at A may be formed at one end with upwardly extending pole pieces or shoes as at 23 whereby the zone of the magnetic field will be extended to 15 a desired height above the liquid level for reasons explained below. The magnets B, B' of which six pairs are shown for each unit, may all be of a like construction. Magnets C, D and E as shown may be shaped with pole pieces 25 conforming to the lower semi-cylindrical end of the magnet compartment and with windings as shown of convenient shapes to fit the space provided in this part of the compartment. In accordance with known practice succeeding magnets 30 pole pieces of the series may have alternate polarities. However, if desired, magnets C, D and E may be so wound that their active outer pole pieces are of the same polarity, to avoid agitation of the particles on the belt while passing around the semi-cylindrical lower end of the magnet compartment. For the same reason if desired, the magnets along the arcuate part of the belt 35 may be similar to those used in magnetic pulleys of copper machines, except semi-circular instead of circular, i.e., with a succession of semi-circular pole pieces of alternate polarity across the belt, so that each particle adhering to the belt will retain its same polarities throughout its travel on the arcuate portion and thus be securely retained 40 in place. In some cases the magnets A and B at least may be in the form of strong permanent magnets instead of electromagnets, thus reducing the manufacturing and operation costs.

In order to lubricate the belt as it passes over 45 the surfaces of the member 20 and to exclude ore particles, etc., from entrance between such surfaces and the belt, lubricating fluid, preferably water, is introduced at spaced points through pipes as at 25, communicating with a vertical header 26 connected at 27 to a suitable source of supply. As shown in Fig. 2, pipes 25 may be sealed through the sheet metal 20 to discharge the lubricating fluid at points along the middle of the belt, the pipes being conveniently arranged between adjacent pairs of magnets. The lubricating fluid as discharged against the middle of the belt, spreads out over the under side of the belt and should be of sufficient volume and subjected to sufficient pressure so that it will slightly float 50 the belt away from the magnet surfaces, and flow outwardly from the edges of the belt, as indicated at 27', Fig. 2, and into the body of water in the tank 10. Thus outward currents of the lubricating fluid at the edges of the belt will prevent ore 55 and gangue particles from getting under the belt.

In order that the lubricating fluid will be free to flow outwardly at all points along the edges of the belt, the belt should be of a width as shown in Fig. 2, substantially less than the width of the tank. Thus there will be no danger of the belt edges contacting with the side walls of the tank and obstructing the outward flow of the lubricant. To also avoid danger of magnetic particles being drawn under the edges of the belt, the magnet pole pieces as shown in Fig. 2 should preferably terminate substantially inwardly of the edges of the belt as shown at 28. This will insure that the magnetic particles will be drawn on to the outer surface of the belt at points inwardly of the belt edges, rather than into the corner areas 27.

As shown in Fig. 1, the belts on alternate separating units are preferably driven in opposite directions. This enables ore to be fed in as by feed troughs or pipes 30, 30' located in alternate spaces between units, while enabling the concentrates to be taken out at each of the intervening spaces between adjacent units. A liquid mixture of the ore introduced through feed pipes 30, 30' may be directed as by plates 31, 31' into proximity of the surfaces of the downwardly moving belt stretches. As the ore falls below the liquid level, most of the magnetic particles thereof will be promptly drawn against the belt together with such gangue as may be enmeshed by the magnetic particles. Such of the remaining gangue as contains no magnetic particles, after it falls below the plates 31 or 31', will be quite free to fall through spaces 32, 32' down to tailings hoppers as shown at 33, 33', for withdrawal through suitable known types of clotures. Meanwhile, magnetized particles while being carried on the downward stretches of the belts, will have their polarities reversed as they pass each of the succeeding magnet pole pieces of alternate polarity. This will result in sufficient agitation of the particles adhering to the belt to cause considerable gangue to be liberated, but at the same time some of the magnetic particles may also be dislodged. While the dislodged gangue will be free to fall to the tailings outlets, any of the dislodged magnetic particles will be attracted sideways and downwardly by the combined actions of the forces of the magnetic field and gravity, back on to the belt. Because the paths through which the particles can fall are elongated and subject throughout to strong magnetic fields, practically all of the magnetic particles will be firmly captured or recaptured on the downward stretches before the lower arcuately curved portions are reached.

Since such effective means is thus provided for recapturing dislodged magnetic particles, the magnetic masses on the down stretch of the belt may be subjected to intense cleaning action from forceful jets of water, applied to the belt for example from spray pipes as at 34. Thus the larger part of the gangue will be separated from the ore in the spaces 32, 32' and will settle into the tailings hoppers. The magnetic particles on the belt including some particles embodying non-magnetic material, will then be carried around the arcuate lower portion of the magnetic field and upwardly on the upward stretch of the belt. At this region particles on the belt, while again passing pole pieces of alternate polarity, may be subjected to a still more intense washing action by water supplied through a series of spray pipes as at 35. This will serve to dislodge such of the particles as embody or comprise any substantial amounts of non-magnetic material. These will

fall into middlings hoppers as at 36, 36'. If magnetic particles are dislodged along the upward stretches, they will have ample opportunity to be attracted sideways and downwardly for recapture on to the belt under the combined forces of gravity and the magnetic fields, as is the case at the downward stretches of the belt. Also if the recaptured particles embody any considerable amount of non-magnetic material, they may be again dislodged by jets from pipes 35 to finally fall into the middlings hopper. Thus by the time the particles arrive at the region of the water line on the upward stretches, they will be free of practically all gangue as well as middlings. Since the particles containing no magnetic material are practically all separated out at the downward stretches of the belt and fall into the tailings hoppers, the middlings particles which are finely separated from the upward stretches will substantially all embody some magnetic material. And since the material on the upward stretches is subjected to intensive and repeated washings with repeated opportunities for dislodged magnetic particles to be recaptured, the middlings will comprise only such particles as embody some non-magnetic material and a small proportion of magnetic material insufficient to classify the particles as concentrates. Thus the amount of middlings which have to be reground and re-treated will be comparatively small.

The manner in which the pipe connections may be made for the spray pipes such as at 34 and 35, is shown at the righthand portion of Fig. 1. That is, pipes 35 for example may be brought to the outside of the tank 10 and connected to a vertical header as at 37, which in turn is connected to a suitable source of supply as at 38.

As the concentrates on the upward belt stretches approach the water line, provision is made for removing therefrom any slime, scum or floating impurities and at the same time to give the concentrates as withdrawn a final thorough washing. This may be accomplished by mounting plates as at 40 at spaced positions from the belt to extend from below the water line to a substantial distance above, and affording a trough space along the face of the belt. Water pipes as at 41 are provided along the top edges of plates 40. These spray pipes as indicated in Fig. 3 may extend inwardly from each side of the machine and be formed with outlets for projecting forceful sheet like jets of water, as at 42, downwardly. The sheet jets 42 have the effect of causing any insecure protruding magnetized masses on the belt to be rolled downwardly and back into the water or back into more compact firmly secured positions on the belt areas. Any slimes which might otherwise be present on the concentrates are washed off. At the same time the water at 42 causes a downwardly flowing stream in the spaces between the plates 40 and the belt, so that the surface of the liquid is kept free of slimes at the points where the concentrates are carried up out of the water.

As the concentrates are carried on the belt upwardly past the pipes 41, they continue to be held on the belt by the magnetic field of the extended pole pieces or shoes 23 on the upper magnets. As the particles are elevated out of this field, they fall into a take-off trough 43. Any of the particles which do not fall from the belt of their own accord, may be washed off to also fall into the trough 43, as by sprays 44. As shown in Fig. 3, the trough 43 may be shaped with a downward inclination in both directions from the

center line of the belt. In order to discharge the concentrates from the trough, a spray pipe 45 may be provided with outlets as at 46, 47 for directing sprays toward both ends respectively of the trough 43. The upper side edges or lip portions of the trough 43 may comprise strips of rubber or other flexible material as at 48 which will yield to the extent necessary to permit the magnetized masses of concentrates to be carried up on the belt without being dislodged until they are above the trough level.

With the embodiment of the invention shown in Fig. 1, it will be apparent that any desired number of separating units may be mounted in closely spaced relation in a single tank, thus saving the expense of separate side walls for tanks individual to each unit and at the same time making economical use of all the space within a single large tank. If desired, it will also be apparent that single separator units or pairs of units may be constructed as shown in Fig. 1. In either case substantially the entire space within the loop of each belt is occupied by magnets and by the drive pulley. Also substantially the whole length and width of each belt except for the areas on the drive pulley are utilized at all times. With the magnetic separators heretofore available so far as is known, only one of the two belt stretches could be used and thus nearly twice as much beltting was required and also twice as many pulleys. The substantial filling of the suspended belt loops with the magnet assemblies, makes it possible to dispense with lower pulleys. This in turn eliminates the difficulties of maintenance of such pulleys and their bearings and shafting in submerged positions. If submerged pulleys are used, there may be a substantial tendency for the particles to get under the belt on the pulleys and into bearings, thus causing excessive wear, in addition to the difficulties of maintaining lubrication and preventing deterioration of submerged operating parts.

In the prior magnetic separators of the types above mentioned, it has been found desirable to have a series of about 21 magnets (or pairs of magnets). With the arrangement of Fig. 1, the number of magnets per unit may be reduced by more than one-half, due to the use of the pole pieces at both ends of each magnet, and because the active field areas are elongated vertically in the normal direction of fall of the particles. While the use of both poles of each magnet necessarily involves the presence of two air gaps in the magnetic circuit of each magnet, viz., at each end of the magnet, with a consequent increase in the reluctance of the circuit, yet such increased reluctance is minimized to a considerable extent when the machine is in operation due to the presence of magnetized masses of particles on the belt, which substantially fill in the air gaps in the magnetic circuits. This is especially true under full load conditions when the presence of strong fields is most important. Also since the number of magnets used is much smaller than heretofore necessary, the amount of current used in the windings of each magnet may be greatly increased without using a greater total amount of current than heretofore necessary. Hence it is possible to economically maintain the magnetic fields at proper strength. Also in gang separators as of Fig. 1, the magnetic fields may be more efficiently used, since the spaces between adjacent units are subjected to the fields of two sets of magnets. This makes possible fairly wide spaces within which tailings and middlings are free to

fall without danger of clogging effects when the machine is run at heavy capacity, and yet insuring that all magnetized particles will be subject to capture and recapture by one or the other of the two belts.

It is also evident that the vertical belt construction with the shortened series of magnets as of Fig. 1 makes possible a large saving in floor and housing space required for the units, as compared with the generally horizontally extending belt arrangements of the separators previously available.

In the embodiment of Fig. 4 a pair of units 50, 51 is mounted in a tank 52. The upper pulley arrangements for the belts may as shown be like those of Fig. 1. With this embodiment, however, only the upward stretches of the belts are utilized. That is, two series of magnets in housings as at 55, 56 respectively are mounted along the rear surfaces of the upward belt stretches, the magnet banks being of the general type and number heretofore used, except that they are arranged with their pole pieces along straight vertical lines instead of along a catenary curve. The under surfaces of the belts may be lubricated as in the case of Fig. 1 by water supplied through pipes as at 57, 58, 59. At the lower ends of the magnets some of the lubricating water may be discharged as through nozzles 60 for preventing particles from being drawn up between the belt and the magnet assemblies. Deflector plates as at 61 may also be provided so that water from the nozzle 60 will pass downwardly between the plates 61 and the belt, as indicated by the arrows, and thus further prevent particles from entering under the belt.

In Fig. 4 the ore to be treated may be introduced as through a feed pipe 62 located in the space between the upward stretches, at a region spaced from the lower ends of the magnet banks. The ore particles from the feed pipe 62 will tend to fall down through the space 63 toward a tailings hopper 64. In so doing, the magnetic particles and masses will be captured and carried up on the belt while the gangue will be free to fall into the tailings hopper. At points above the feed pipe 62, the particles on the belts may be subjected to intense washing action by jets from spray pipes as at 65. Here the action will be similar to that between the upward belt stretches of Fig. 1. The concentrates may be removed by the same type of means provided in Fig. 1, corresponding parts for that purpose in Fig. 4 being identified by the same reference characters as in Fig. 1, accompanied by prime marks. In Fig. 4 the liquid level is indicated at 66. As the concentrates pass above this level, they may be subjected to further washing from sprays as at 67. The material which is dislodged by the sprays 67 may be deflected back toward the belts at the water line as by a curved deflector plate 68.

The lower end of the belt loops in Fig. 4 may pass over arcuately curved surfaces, these as shown being in the form of pulleys 70.

It will be apparent that the embodiment of Fig. 4 provides a convenient arrangement for pairs of separating units. This form also is particularly applicable to situations where it is desired to separate the ore into two parts, namely tailings and concentrates, without middlings.

The construction shown in Fig. 5 may be the same as that of Fig. 4, except that Fig. 5 illustrates various novel possibilities as to the relative arrangements of the north and south poles

of the magnets. For example, it is possible to so arrange the magnets that the pole pieces which face each other will be of the same polarity, viz., so as to maintain opposing fields respectively at each side of the space between each pair of units. This is shown at the lower portions of the banks of magnets in Fig. 5. In some cases, however, it may be found desirable to mount the magnets as shown in the mid portion of Fig. 5 where the magnets for one unit are staggered in position with respect to those of the other unit. This will create a field which under some conditions may tend to cause falling magnetic particles to assume a somewhat zigzag path, thus more effectively freeing the particles of gangue. As shown at the upper part of Fig. 5, the opposing pole pieces if desired may be of opposite polarity, thus giving the fields therebetween further different characteristics. The particular arrangement or combination of arrangements of pole pieces found preferable, may depend upon the nature of the ore being treated. One or another of the arrangements may be found most effective with ore particles of certain sizes, or where the gangue has peculiar characteristics.

It will be apparent that the various different arrangements of the polarities of the magnets as shown in Fig. 5 may also be used with the separator units of either Fig. 1 or Fig. 4, either for the entire magnet banks or portions thereof.

While the invention in its various presently preferred forms is particularly adapted to separators of the submerged-belt type, it will be apparent that some of the features of the invention as defined in the appended claims are not limited to machines of that type.

Certain improved embodiments of the invention are disclosed and claimed in applicant's co-pending application Serial No. 793,714, filed December 24, 1947.

While the invention has been described in detail with respect to particular preferred examples, it will be understood by those skilled in the art after understanding the invention that various changes and modifications may be made without departing from the spirit and scope of the invention, and it is intended therefore in the appended claims to cover all such changes and modifications.

What is claimed as new and desired to be secured by Letters Patent is:

1. A magnetic separator comprising a tank for receiving a liquid mixture of magnetic particles and other material to be separated therefrom, a belt extending in the tank, means for supporting and driving said belt with a stretch thereof running upward substantially vertically from out of the liquid, and whereby an extended portion of such stretch is suspended in a position below the liquid level without substantial sagging or deviation from a vertical plane, means for feeding the mixture into the tank at a position spaced substantially from the region where said stretch portion passes up out of the liquid, and a plurality of magnets with pole pieces in alignment along one surface of said upwardly running stretch of the belt, whereby magnetic particles are caused to adhere to the opposite surface of said upwardly running stretch and be carried up out of the liquid.

2. A magnetic separator comprising a tank for receiving a liquid mixture of magnetic particles and other material to be separated therefrom, a belt extending in the tank, means for supporting and driving said belt with a stretch thereof run-

ning upward substantially vertically, whereby at least a portion of such stretch is suspended in a position below the liquid level without substantial sagging or deviation from a vertical plane, a plurality of magnets with pole pieces in alignment along one surface of said portion of the belt, whereby magnetic particles are caused to adhere to the opposite surface of said portion and be carried up out of the liquid, means for feeding the mixture into the tank at a submerged position on said opposite surface intermediate the ends of said alignment of pole pieces, whereby portions of the mixture may settle through the field of the lower pole pieces countercurrent to the travel of the magnetic particles carried up on the belt, and means above the liquid level for carrying the magnetic particles from the belt.

3. A magnetic separator comprising a tank for receiving a liquid mixture of magnetic particles and other material to be separated therefrom, a belt extending in the tank, means for supporting and driving said belt with a stretch thereof running upward substantially vertically from out of the liquid, and whereby an extended portion of such stretch is suspended in a position below the liquid level without substantial sagging or deviation from a vertical plane, means for feeding the mixture into the tank at a position spaced substantially from the region where said stretch portion passes up out of the liquid, a plurality of magnets with pole pieces in alignment along one surface of said portion of the belt, whereby magnetic particles are caused to adhere to the opposite surface of said portion and be carried up out of the liquid, and means both below and above the liquid level for forcefully applying water jets to the magnetic particles on the belt for dislodging and removing non-magnetic material therefrom.

4. A magnetic separator comprising a pair of belts, a tank for receiving a liquid mixture of the material to be separated, means for suspending and driving said belts respectively with upwardly running stretches in said tank, said stretches including portions which run for a substantial distance in generally parallel relation and with opposed faces spaced apart by a submerged separating zone, and two series of magnets arranged along the back surfaces of said stretches respectively and subjecting said zone to a magnetic field for causing magnetic material to be attracted to said stretches and carried up out of said zone.

5. A magnetic separator comprising a pair of belts, a tank for receiving a liquid mixture to be separated, means for suspending and driving said belts respectively with upwardly running stretches in said tank and with opposed faces spaced apart by a submerged separating zone, and two series of magnets arranged along the back surfaces of said stretches respectively and subjecting said zone to a magnetic field for causing magnetic material to be attracted to said stretches and carried up out of said zone, alternate magnets in each of said series having their pole pieces adjacent the belt stretch, of opposite polarity, and the pole pieces of one series being of opposite polarity with respect to the nearest pole pieces respectively of the other series.

6. A magnetic separator comprising a pair of belts, a tank for receiving a liquid mixture to be separated, means for suspending and driving said belts respectively with upwardly running stretches in said tank and with opposed faces spaced apart by a submerged separating zone, and two series of magnets arranged along the back

surfaces of said stretches respectively and subjecting said zone to a magnetic field for causing magnetic material to be attracted to said stretches and carried up out of said zone, alternate magnets in each of said series having their pole pieces adjacent the belt stretch, of opposite polarity, and the pole pieces of one series being of the same polarity as the nearest pole pieces respectively of the other series.

7. In a magnetic separator, the combination of an upwardly running carrier area, magnets along one surface of said carrier area for causing magnetic material to be attracted to the opposite surface and carried upwardly, a trough extending generally transversely of the direction of movement of an upper portion of said carrier area, a flexible lip along the edge of said trough close to said opposite surface and permitting the magnetic material on the carrier to be carried up past the trough, and means above the trough for dislodging the magnetic material from the carrier, to fall into said trough.

8. A magnetic separator comprising a generally U-shaped surface, a belt, means for supporting and driving said belt with a lower loop having a stretch passing generally vertically downwardly over one side of said surface and thence around to provide another stretch running generally vertically upwardly over the other side of said surface, magnetic means within said U-shaped surface for causing magnetic material to be attracted to the outside surfaces of both of said stretches and to the outside surface of the belt as it passes around the curved base portion of the U-shaped surface connecting said stretches, means to feed material to be separated against said downward stretch, and means for carrying separated magnetic particles from the belt after being carried up along a substantial portion of said upward stretch.

9. A magnetic separator comprising means forming a generally U-shaped surface, a belt, means for supporting and driving said belt with a lower loop having a stretch passing downwardly over one side of said surface and thence around to provide another stretch running upwardly over the other side of said surface, a series of superposed magnets within said U-shaped surface for causing magnetic material to be attracted to the outside surfaces of both of said stretches, said magnets being each arranged with one pole maintaining a field at said downward stretch and its other pole maintaining a field at said upward stretch, means to feed material to be separated against said downward stretch, and means for carrying separated magnetic particles from the belt after being carried up along a substantial portion of said upward stretch.

10. A magnetic separator comprising means forming a generally U-shaped surface, a belt, means for supporting and driving said belt with a lower loop having a stretch passing downwardly over one side of said surface and thence around to provide another stretch running upwardly over the other side of said surface, magnetic means within said U-shaped surface for causing magnetic material to be attracted to the outside surfaces of both of said stretches, means to feed material to be separated against said downward stretch, means for carrying separated magnetic particles from the belt after being carried up along a substantial portion of said upward stretch, and tank means within which said loop is suspended, including a tailings hopper be-

low said downward stretch and a middlings hopper below said upward stretch.

11. A magnetic separator comprising a plurality of generally U-shaped surfaces arranged side-by-side in spaced relation to provide a separating zone between each pair, a corresponding plurality of belts, means for supporting and driving said belts, each with a lower loop having a stretch passing downwardly over one side of one of said U-shaped surfaces and thence around to provide another stretch running upwardly over the other side of the same U-shaped surface, and with upward stretches of one belt facing an upward stretch of another belt, and magnetic means within said U-shaped surfaces for causing magnetic material to be attracted to the outside surfaces of both the downward and upward stretches.

12. A magnetic separator comprising a plurality of generally U-shaped surfaces arranged side-by-side in spaced relation to provide a separating zone between each pair, a corresponding plurality of belts, means for supporting and driving said belts, each with a lower loop having a stretch passing downwardly over one side of one of said U-shaped surfaces and thence around to provide another stretch running upwardly over the other side of the same U-shaped surface, and with upward stretches of one belt facing an upward stretch of another belt, magnetic means within said U-shaped surfaces for causing magnetic material to be attracted to the outside surfaces of both the downward and upward stretches, and tailings and middlings hoppers respectively below downward and upward stretches.

13. A magnetic separator comprising a plurality of generally U-shaped surfaces arranged side-by-side in spaced relation to provide a separating zone between each pair, a corresponding plurality of belts, means for supporting and driving said belts, each with a lower loop having a stretch passing downwardly over one side of one of said U-shaped surfaces and thence around to provide another stretch running upwardly over the other side of the same U-shaped surface, and with upward stretches of one belt facing an upward stretch of another belt, and magnetic means within said U-shaped surfaces for causing magnetic material to be attracted to the outside surfaces of both the downward and upward stretches, said magnetic means including magnets each with cores having one pole maintaining a field active for separation purposes at a downward stretch and another pole maintaining a field active for separation purposes at an upward stretch.

14. In a magnetic separator, a belt, means for supporting and driving said belt in a position to have a vertically elongated suspended loop including a generally vertical downward active stretch and a generally vertical upward active stretch, means for applying mixture to be separated to the belt at a region near the upper end of such downward stretch, means for removing separated magnetic material from the belt at a region near the upper portion of said upward stretch, and a series of stationary magnet pole pieces within said loop, said series extending along said downward stretch thence around within the bottom of the loop and then up along said upward stretch.

15. In a magnetic separator, a liquid basin, a series of drive pulleys on substantially parallel horizontal axes side-by-side above the liquid

level, a series of belts, each suspended by one of said pulleys and each having an elongated loop extending down below the liquid level, a series of magnet pole pieces arranged along the inside of the submerged portions of each loop, said loops being spaced apart by separating zones, and means for driving alternate pulleys in opposite directions, whereby at alternate separating zones, the facing belt stretches both move downwardly and at intervening zones the facing belt stretches both move upwardly.

16. In a magnetic separator, a liquid basin, a series of drive pulleys on substantially parallel horizontal axes side-by-side above the liquid level, a series of belts, each suspended by one of said pulleys and each having an elongated loop extending down below the liquid level, a series of magnet pole pieces arranged along the inside of the submerged portions of each loop, said loops being spaced apart by separating zones, means for driving alternate pulleys in opposite directions, whereby at alternate separating zones, the facing belt stretches both move downwardly and at intervening zones the facing belt stretches both move upwardly, means for feeding material to be separated into the zones at downwardly traveling stretches, and means for removing recovered magnetic material from the upwardly traveling stretches.

17. A magnetic separator comprising a pair of generally U-shaped surfaces arranged side-by-side in spaced relation to provide a separating zone therebetween, said surfaces including stationary portions forming the base portions of the U shapes, a pair of belts, means for supporting and driving said belts each with a lower loop having a stretch passing downwardly over one side of one of said U-shaped surfaces and thence around to provide another stretch running upwardly over the other side of the same U-shaped surface, and with the upward stretch of one belt facing the upward stretch of the other belt, and magnetic means within said U-shaped surfaces for causing magnetic material to be attracted to the outside surfaces of said belts as the stretches thereof pass downwardly around and upwardly.

18. A magnetic separator comprising a pair of generally U-shaped surfaces arranged side-by-side in spaced relation to provide a separating zone therebetween, said surfaces including stationary portions forming the base portions of the U shapes, a pair of belts, means for supporting and driving said belts each with a lower loop having a stretch passing downwardly over one side of one of said U-shaped surfaces and thence around to provide another stretch running upwardly over the other side of the same U-shaped surface, a liquid basin within which said U-shaped surfaces and the belt loops thereon may be submerged, means for supplying material to be separated on to the downward belt stretches, means for removing tailings from beneath said downward stretches, means for removing middlings from beneath said upward stretches, and means for establishing magnetic fields tending to attract magnetic particles onto said stretches.

19. In a magnetic separator, a tank adapted to contain a body of liquid, a stationary U-shaped compartment therein containing an assembly of magnets, a travelling belt having a loop suspend-

ed in the tank with the inside surface of the loop contacting with the exterior surface of said compartment within the tank, and means for applying a mixture of magnetic and non-magnetic material to be separated onto said belt at one point and for separately removing the magnetic and non-magnetic material at other points, at least one side of said U-shaped compartment being constructed and arranged to open directly to the exterior of the tank to afford ready access to said magnet assembly without disturbance of the liquid in the tank or the belt suspended therein.

20. In a magnetic separator, a tank adapted to contain a body of liquid, a plurality of spaced compartments therein each containing an assembly of magnets, at least one side of each of said compartments opening to the exterior of the tank to afford ready access to said magnet assemblies, a plurality of belts each having a loop suspended in the tank to extend respectively about said compartments, and means above the liquid line for so suspending and driving said belts that facing generally vertical stretches of successive belts will travel in the same direction.

21. In a magnetic separator, a tank adapted to contain a body of liquid, a plurality of spaced compartments therein each containing an assembly of magnets, at least one side of each of said compartments opening to the exterior of the tank to afford ready access to said magnet assemblies, a plurality of belts each having a loop suspended in the tank to extend respectively about said compartments, and means above the liquid line for so suspending and driving said belts that facing generally vertical stretches of successive belts will travel in the same direction, means for feeding material to be treated onto the downwardly running belt stretches, tailings hoppers being provided at the bottom of the tank beneath the downwardly running facing stretches, and middlings hoppers alternating in position with said tailings hoppers and located beneath the upwardly running facing stretches.

ROBERT E. CROCKETT.
